The ornamental design for an ice compartment for a refrigerator fresh food compartment, as shown and described.

DESCRIPTION

FIG. 1 is a front elevation view of an ice compartment for a refrigerator fresh food compartment showing our new design;

FIG. 2 is a right side elevation view thereof, shown without environment;

FIG. 3 is a bottom plan view thereof; and,

FIG. 4 is a perspective view of FIG. 1.

The broken lines represent environmental structure or unclaimed portions of the ice compartment for a refrigerator fresh food compartment and do not form a part of the claimed design.
